CLAIM

The ornamental design for a curved pedal, as shown and described.

DESCRIPTION

FIG. 1 is a right side view of a first embodiment of a curved pedal, showing my new design, in an exemplary environment;

FIG. 2 is a left side view thereof;

FIG. 3 is a top view thereof;

FIG. 4 is a bottom view thereof;

FIG. 5 is a rear view thereof;

FIG. 6 is a front view thereof;

FIG. 7 is a right side view of a second embodiment of a curved pedal, showing my new design, in an exemplary environment;

FIG. 8 is a left side view thereof;

FIG. 9 is a top view thereof;

FIG. 10 is a bottom view thereof;

FIG. 11 is a rear view thereof; and,

FIG. 12 is a front view thereof.

In the drawings, portions drawn in solid line indicate claimed subject matter. Portions drawn in dashed or dotted line indicate unclaimed environment and form no part of the claimed design. Dot-dash chain lines indicate boundaries between claimed subject matter and unclaimed environment, and form no part of the claimed design.
